(57) **CLAIM**

The ornamental design for a stairlift chair, as shown and described.

DESCRIPTION

FIG. 1 is a perspective view of a stairlift chair showing my design;

FIG. 2 is a front view thereof;

FIG. 3 is a back view thereof;

FIG. 4 is a perspective back right view thereof;

FIG. 5 is a right side view thereof;

FIG. 6 is a left side view thereof;

FIG. 7 is a top plan view thereof;

FIG. 8 is a bottom plan view thereof;

FIG. 9 is a perspective front right view thereof, in which each of a seat pan, a footrest, and armrests of the stairlift chair are in a folded-up state;

FIG. 10 is a front view of the stairlift chair, shown in the folded-up state of FIG. 9;

FIG. 11 is a back view of the stairlift chair, shown in the folded-up state of FIG. 9;

FIG. 12 is a right side view of the stairlift chair, shown in the folded-up state of FIG. 9;

FIG. 13 is a left side view of the stairlift chair, shown in the folded-up state of FIG. 9;

FIG. 14 is a top plan view of the stairlift chair, shown in the folded-up state of FIG. 9; and,

FIG. 15 is a bottom plan view of the stairlift chair, shown in the folded-up state of FIG. 9.
